A technical drawing showing a cross-section of a metal strip. The strip has a central circular hole. Above the hole, the number '25' is written. Below the hole, the number '26' is written. To the left of the strip, the number '113' is written above a horizontal line. To the right of the strip, the number '123' is written above a horizontal line. Below the strip, the text 'In re Freeman' is written, followed by 'by Watson & Cid Attorneys'.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

ENGINE.

1,113,510.

Specification of Letters Patent. Patented Oct. 13, 1914.

Application filed March 18, 1909. Serial No. 484,231.

To all whom it may concern:

Be it known that I, MILTON TIBBETTS, a citizen of the United States, residing at Detroit, in the county of Wayne and State 5 of Michigan, have invented certain new and useful Improvements in Engines, of which the following is a specification.

This invention relates to engines in the broadest sense, including motors of all kinds, 10 compressors and blowing engines, pumps, and similar devices, and particularly to internal combustion motors employing sliding valves.

Engines have heretofore been constructed 15 in which the inlet and outlet ports are arranged opposite each other and in approximately the same plane and in which a pair of sleeves surround the piston and have co-operating ports to open and close the cylinder ports, and it is improvements upon and additions to such motors that constitute the subject-matter of my present invention.

One of the objects of my invention is to obtain a larger, quicker and more positive 20 opening and closing of the inlet and exhaust ports of the engine than has heretofore been accomplished.

Another object is to provide a simple and effective air compressing and oil pumping 25 mechanism for the engine without materially increasing the working parts.

These and other objects will appear in the following description taken in connection with the drawings, in which,—

Figure 1 is a transverse sectional view 30 through the center of the cylinder of an engine embodying some of the features of my invention; Fig. 2 is an enlarged vertical section on the line 2—2 of Fig. 1; Fig. 3 is a section similar to Fig. 1 showing an engine 35 embodying another form of my invention; Fig. 4 is a section on the line 4—4 of Fig. 3; Fig. 5 is a fragmentary sectional view approximately on the line 5—5 of Fig. 4; Fig. 40 6 is a section similar to Figs. 1 and 3, showing an engine embodying another form 45 of my invention; Figs. 7 to 11 are enlarged sectional views showing one form of the pumping mechanism with the moving parts 50 in various positions; Figs. 12 to 15 are enlarged sectional views showing another form 55 of the pumping mechanism with the moving parts in various positions; Fig. 16 is a dia-

grammatic view; and Fig. 17 is a diagram showing the opening and closing of the ports 55 in the pump illustrated in Figs. 12 to 15.

Referring particularly to Figs. 1 and 2, 60 20 represents the casing or cylinder of the engine having double walls forming a water jacket 21. This casing is mounted on the upper or supporting section 22 of the crank case and the crank shaft 23 is mounted in bearings 24 between said section 22 and the removable intermediate section 25. The bottom of the crank case is closed by the removable cover 26 which forms an oil well into which the cranks 27 dip as they revolve thus lubricating by the splash system the various working parts within the crank case. Also mounted to rotate in the supporting section 70 22 parallel with the crank shaft is a valve operating shaft 28 having eccentrics or cranks 29 for reciprocating the valves hereinafter described. This shaft 28 is driven by the crank shaft by two-to-one gearing 75 such as illustrated in Fig. 3, whereby the motor is operated on the four stroke cycle.

The upper end of the casing or cylinder 20 is closed by a removable end wall or head 30, the cylindrical shaped central part 31 of 80 which extends down into the casing as shown, leaving an annular space 32 between its periphery and the inner wall of the casing. This head is also water jacketed as shown, its water jacket being connected with the jacket 21 of the cylinder and it is formed with horizontal ports 33, which nearly divide it, the lower part 34 being suspended only by the hollow arms 35 through which the water passes to the jacket 36. Said lower 90 part 34 is in the form of a hollow ring with the ports 33 along its upper edge and thus these ports are in constant communication with the interior of the casing or cylinder 20. A spark plug 37 is provided in the central part of the head for igniting the charge in the cylinder as is well understood.

The casing or cylinder 20 is formed with inlet and exhaust chambers 38 and 39, which extend parallel with each other entirely 100 around the casing, being separated by a thin partition 40. The inlet chamber 38 communicates with the inlet pipe 41 and with the ports 42 in the casing wall, which ports 42 are arranged approximately in a plane 105 with the ports 33 in the head above de-

scribed, and the exhaust chamber 39 communicates with the exhaust pipe 43 and with the ports 44 in the casing wall, which ports 44 extend practically around the cylinder 5 and are arranged just below the lower edge of the part 34 of the head above described.

It will be understood that with the above arrangement of chambers and ports the total area of the ports will be greater than in 10 engines employing opposite inlet and outlet ports where each port extends less than half way around the cylinder, and when the engine is used as an explosive motor the hot exhaust gases passing through the exhaust chamber will tend to warm the gases 15 entering the inlet chamber.

Guided by the inner wall of the casing 20 and extending into the annular space 32 is a sliding valve shown in the form of 20 a cylindrical sleeve 50 having two sets of ports 51 and 52, each of which sets extends entirely around the sleeve, the sections above and below the ports being connected by webs. The ports 51 are adapted to register 25 with the inlet ports 42 and consequently with the ports 33 in the head 30, and the ports 52 are adapted to register with the exhaust ports 44. Sliding within the sleeve 50 and also extending into the space 32 is 30 another similar sleeve or sliding valve 53 which has similar sets of ports 54 and 55 which also extend entirely around the sleeve and are adapted to respectively register at times with the ports 42 and 44 and 35 with the ports 51 and 52. The periphery of the central part 31 of the head 30 is provided with split packing rings 56 above and below the ports 33 whereby the ports 54 and 55 are made tight when said ports are 40 over these rings which is preferably during the compression and firing strokes of the motor.

The sleeve 53 above described forms the piston barrel, the piston 57 being shown 45 therein and connected to the crank shaft by the connecting rod 58.

The sleeves 50 and 53 are reciprocated by the cranks 29 on the shaft 28 through the rods 59 and 60 respectively, and said 50 cranks 29 are arranged at approximately 90° apart with the inner sleeve connected to the leading crank whereby the outer sleeve follows the inner sleeve at a quarter period from it, and the various ports above described are so arranged and proportioned that the inlet port will be open to the interior of the inner sleeve or piston barrel and the exhaust port closed thereto during the suction stroke of the piston, both inlet 55 and exhaust ports will be closed during the following compression and firing strokes of the piston, and the exhaust port open and the inlet closed during the following exhaust stroke, as is usual in four stroke cycle 60 motors. With the sleeves so arranged about

a quarter period apart it is evident that there will be a relative movement between the sleeves and they will be caused to recede from and approach toward each other once during each cycle of operation of the 70 motor. It is also evident that the outer sleeve will reciprocate relative to the cylinder, and it is one of the objects of this invention to utilize one or both of these relative movements to pump oil to various parts 75 of the motor or to pump air to a compression tank for various uses, or for other similar purposes.

The pump shown in Figs. 1 and 2 is formed in the two sleeves 50 and 53, the outer sleeve 53 having its bore enlarged at the lower end as shown at 61 and the inner sleeve 50 having an annular enlargement 62 adapted to operate in the enlarged bore 61. Thus it will be seen that the relative 85 movement of the sleeves will cause the pump chamber 63 between the sleeves to be alternately enlarged and contracted so that by arranging suitable ports in the sleeves such relative movement may be utilized as 90 a pump for various purposes. In said Figs. 1 and 2, the lower end of the outer sleeve is provided with an outwardly extending annular ledge 64, having a flange 65, which ledge is adapted to catch the oil splashed 95 by the cranks 27 revolving in the crank case, and openings 66 communicate with the interior of the pump chamber 63 when the sleeves are farthest apart, whereby the oil caught by said ledge is drawn into the 100 chamber, and as the sleeves then come together the oil is forced up through check valve 67 and passage 68 to a passage 69 formed between the sleeves as shown. Said passage 69 leads part of the oil upwardly to 105 the top of the sleeve and part of it is led around the sleeve by distributing grooves 70 by which the sleeves are lubricated. If a superfluous amount of oil reaches the space 32 between the head and the casing 110 it will flow by gravity or pressure from the pump through the overflow passage 71 formed between the outer sleeve and the inner wall of the casing. Thus, so long as there is a supply of oil in the crank case 115 it will be splashed onto the ledge 64, pumped up through the various oil passages and fed to the distributing grooves 70, and the surplus finds its way down from the head through the overflow passage to the crank 120 case again, or is caught immediately by the ledge and returned by the pump. Small openings 72 may be formed in the outer sleeve to aid in the lubrication of the cylinder wall. Thus a constant flow of oil is 125 kept up and the sleeves and cylinder are amply lubricated.

It will be understood that the passages 69 and 71 reach the tops of the sleeves by being partly formed in webs between the va- 130

rious ports, these webs being preferably formed opposite the hollow arms 35 of the head.

Another form of two sleeve motor is illustrated in Figs. 3 to 5, the main difference between this form and the above described form being that the sleeves, instead of being superposed, are arranged end to end and each sleeve controls its separate port, the upper sleeve 100 moving up and down to open and close the inlet port 42, and the lower sleeve 101 moving down and up to open and close the exhaust port 41. The upper sleeve 100 is reciprocated by rods 102 which are connected to ears 103 on the sleeve and extend down through vertical guideways 104 into the crank case where their lower ends are connected by rods 105 with cranks and eccentricities 29 on the valve operating shafts 28. The lower sleeve 101 is connected through ears 106 and rods 107 with its respective cranks or eccentricities on the shafts 28 as will be clearly seen. In this form of the invention, I have shown two operating shafts 28, one on each side of the motor, and they are identical in construction and are rotated by two-to-one gearing from the crank shaft, such as large gears 108 and small gear 109. The use of two operating shafts guards against twisting or binding of the sleeves that might occur if only one shaft was used. Corresponding parts of the motor shown in Fig. 3 are lettered the same as those in the motor shown in Fig. 1. As there is but one sleeve in the lower end of the cylinder in Fig. 3, the oil pump is formed between the sleeve and cylinder, the cylinder bore being enlarged at 61^a as shown and the lower end of the sleeve 101 being increased in size as at 62^a, to fit said enlarged bore. In Fig. 3 the oil pump inlet is shown at 110 and the outlet at 111, and each of these may be in the form of a check valve like that illustrated at 67 in Fig. 1. The operation of the pump is obvious; the sleeve on the down stroke creating a vacuum in the chamber 63 which draws the oil through the inlet 110 as the sleeve reaches the bottom of its stroke, and the return or up stroke of the sleeve forcing this oil through the outlet 111 from which it may be led through pipes to any desired points. If desirable the inlet 110 may be arranged at the top of the chamber 63 instead of at the bottom as shown.

In Fig. 6 another form of the invention is shown in which two superposed sleeve valves are employed, the inner sleeve 50^a being similar to the inner sleeve shown in Fig. 1, but the outer sleeve 53^a is shorter than the inner and co-operates only in controlling the lower or exhaust ports, the inner sleeve alone controlling the inlet ports. Except as stated and as to a slight difference in the timing of the sleeves made necessary by their difference in construction, this motor is similar to

those previously described and like parts are similarly designated.

Figs. 7 to 11 illustrate a form of oil or air pump differing slightly in its method of operation from those previously described, but applicable to any form of motor employing a plurality of superposed relatively sliding valves. This form of pump is particularly designed for pumping a very small quantity of oil at each stroke, but may of course be used in other ways by varying the size and capacity of the chambers and ports. A pump chamber 63 is formed between the sleeves 50 and 53 as in Fig. 1 and a port (or series of ports) 66^a is formed in the outer sleeve in position to be open to the chamber 63 when the sleeves are at their maximum distance apart, whereby a charge of air from the crank case is drawn into the chamber. As the sleeves then approach each other the chamber 63 is of course contracted and the air therein compressed, its only outlet being through passage 112 suitably formed in the inner sleeve or between it and the outer sleeve. The outlet 113 of this passage is arranged to register with a port or pocket 114 extending entirely through the outer sleeve 50 at the same time that said pocket registers with the outlet port 111^a formed in the cylinder wall, whereby the air compressed in said chamber rushes through said pocket and is discharged into said outlet port or pipe 111^a. While the charge of air is being drawn into and compressed within the chamber 63 as above described, the port or pocket 114 is in register with the oil inlet port 40^a, which port in this instance is elongated vertically so that the pocket may register with it for a considerable period of the stroke of the outer sleeve, and the oil in said port or pipe 40^a flows by gravity or pressure into the pocket 114, so that when the charge of air rushes through said pocket as above set forth it carries with it the charge of oil therein contained and from the pipe 111^a it is fed to the various points of the motor to be lubricated, or to an oil compression tank as desired. The quantity of oil to be fed at each charge may be regulated by varying the size of the pocket 114 or by the needle valve 115. The various positions of the sleeves shown in Figs. 7 to 11 amply illustrate the operation of the pump. It will of course be understood that the pocket 114 may be elongated upwardly instead of the port 40^a and the same result would be accomplished.

In the form of pump illustrated in Figs. 12 to 17 there are no check valves and there is no communication with the crank case. The inlet port 110^b and the outlet port 111^b are arranged as shown, each being slightly elongated longitudinally of the cylinder, so that the port 113^b of passage 112^b leading from the pump chamber 63, registers 130

with the inlet 110^b during the suction stroke of the pump and with the outlet 111^b during the compression stroke of the pump. Thus a considerable charge of oil may be drawn 5 into the pump and discharged through the port 111^b and from thence led to any desired points, or the pump may be used to compress air and store it in a pressure tank, from whence it may be used for various purposes about the motor as illustrated in Fig. 16. Referring to said figure, 20 represents the motor casing, 110^b the air inlet for the pump inside the motor, and 111^b the air outlet. The compressed air is led by pipe 116 10 to the pressure tank 117, from which tank it may be piped as desired through reducing valve 118 and pipes 119, 120 and 121 to the oil and gasoline tanks 135 and 136, respectively, of the motor, whereby oil and 15 gasoline may be fed under pressure. Also a pipe 122 may convey the air to a distributing valve 123 and through pipe 124 to the cylinder of the motor for starting the same. The three-way cock 125 controls admission of air to the pipes 119 and 122. Air 20 may also be led from the tank 117 through cock 126 and flexible tube 127 to the tires of the vehicle when the engine is used in a motor vehicle. Other and various uses may 25 be made of the pump and its appurtenances and the above are described merely as illustrating some of its more important features, and are not intended to limit its uses to those shown.

35 In Fig. 17 the relative positions of the various ports are clearly illustrated in a complete cycle of operation of the pump. The cylinder ports are shown at 110^b and 111^b, the partition between them at 128, and 40 the port in the outer sleeve at 113^b. The path of travel of said port 113^b is clearly shown and the path of travel of the inner sleeve is indicated by the line 53^b. Thus it will be observed that the sleeves are farthest 45 apart at about the point 129 which is just as the port 113^b is passing out of register with the inlet port, and that the sleeves are closest together at about the point 130 which is just as said port is passing out of register 50 with the outlet port. During the time the port 113^b is passing over the partition 128 the pump slightly compresses its charge or creates a vacuum within it as the case may be.

55 It is evident that the ports and passages may be formed in the cylinder and sleeves in various ways and the invention is not limited to the specific forms shown. It is also evident that the chamber 63 may be 60 formed in various ways other than that shown, and it need not extend entirely around the sleeves but may be formed in a part only of their circumference.

In multi-cylinder motors of the character 65 above described, the sleeve pump of one cyl-

inder may be connected to one class of distributing devices and the pump of another cylinder to another such class, or the sleeve pumps of all the cylinders may be connected to a single distributing system, as desired. 70

Having thus described my invention, what I claim is:

1. The combination with a casing having a head extending into one end thereof, said casing having inlet and outlet ports in different transverse planes and said head having a port coöperating with one of said casing ports to open said casing port to the interior of the casing, of a plurality of valves sliding between said casing and head 75 and controlling the ports therein.

2. The combination with a casing having a head extending into one end thereof, said casing having inlet and outlet ports in different transverse planes and one of which is 80 above the lower end of the extension on said head, of a plurality of coaxial sliding valves arranged between the extended part of said head and the surrounding casing and controlling said ports, and positive means for 85 sliding said valves.

3. The combination with a casing having a head extending into one end thereof, said casing having inlet and outlet ports in different transverse planes, and said head having a port coöperating with one of said casing ports, of a plurality of coaxial sliding valves controlling all of said ports, and 90 means for sliding said valves.

4. The combination with a casing having a head extending into one end thereof, said casing having inlet and outlet ports in different transverse planes and said head having a port coöperating with one of said casing ports, of a plurality of coaxial sliding valves controlling all of said ports, and 100 positive means for sliding said valves.

5. The combination with a casing having a head extending into one end thereof, said casing having inlet and outlet ports in different transverse planes and said head having a port coöperating with one of said casing ports, of a plurality of coaxial sliding valves between the extended part of the head and the surrounding casing and controlling all of said ports, and means for 110 sliding said valves.

6. The combination with a casing having a head extending into one end thereof, said casing having inlet and outlet ports in different transverse planes and said head having a port coöperating with one of said casing ports, of a plurality of coaxial sliding valves between the extended part of the head and the surrounding casing and controlling all of said ports, and positive means 120 for sliding said valves.

7. In an engine, the combination with a casing and a piston, of a pair of superposed sleeve valves surrounding the piston, one of 125

- 5 said valves having a recess and the other having a projection arranged in said recess and coöperating with the latter to produce a pumping action by their relative movement.
8. In an engine, the combination with a cylinder and a relatively sliding valve, of a pump of which said valve forms a part, the ports of said pump being independent of the 10 inlet and outlet ports of the engine.
9. In a motor having two valve sleeves sliding one on the other, a pump barrel formed in one of said sleeves, a piston formed in the other, and means for relatively reciprocating said sleeves.
10. In a motor having two valve sleeves sliding one on the other, a pump barrel formed in one of said sleeves, a piston formed in the other, said sleeves having 15 inlet and outlet ports for said pump barrel, and means for relatively reciprocating said sleeves.
11. In a motor, the combination with the casing having ports, and the piston working 20 in said casing, of a pair of sleeves between said piston and casing and controlling said ports, of a pump formed in the lower ends of said sleeves and operated by the relative movement thereof, said sleeves having 25 passages leading from the pump chamber to various points on the surfaces of the sleeves, and means for relatively reciprocating said sleeves.
12. In a motor, the combination with a 30 casing or cylinder having ports, a piston working in the casing, and a plurality of sliding valves controlling said ports, of a pump formed in said valves, and means for reciprocating said valves relative to the casing and to each other.
13. In a motor, the combination with the 35 casing having ports, a plurality of sliding valves in the casing controlling said ports, a piston, connecting rod and crank shaft 40 suitably connected, the piston working in the casing, means for sliding said valves, and a crank case including the working parts of the motor and adapted to contain oil for lubricating the said parts by the splash system, of means operated by said valves for forcing said oil between the 45 valves.
14. In a motor, the combination with the 50 casing having ports, a plurality of sliding valves in the casing controlling said ports, a piston, connecting rod and crank shaft 55 suitably connected, the piston working in the casing, means for sliding said valves, and a crank case enclosing the working parts of the motor and adapted to contain oil for lubricating the said parts by the splash system, of means operated by said valves for forcing said oil between the valves and between one of the valves and the casing.
- 60 15. In a motor, the combination with the 65 casing having ports, a plurality of sliding valves in the casing controlling said ports, a piston, connecting rod and crank shaft 70 suitably connected, the piston working in the casing, means for sliding said valves, and a crank case enclosing the working parts of the motor and adapted to contain oil for lubricating the said parts by the splash system, of means operated by said valves for forcing said oil to the casing head, and 75 means by which said oil may return from the head to the crank case.
16. In a motor, the combination with the 80 casing having ports, a plurality of sliding valves in the casing controlling said ports, a piston, connecting rod and crank shaft 85 suitably connected, the piston working in the casing, means for sliding said valves, and a crank case enclosing the working parts of the motor and adapted to contain oil for lubricating the said parts by the splash system, of a pump formed in said valves, and means 90 for supplying the oil in the crank case to said pump.
17. In a motor, the combination with the 95 casing having ports, a plurality of sliding valves in the casing controlling said ports, a piston, connecting rod and crank shaft 100 suitably connected, the piston working in the casing, means for sliding the valves, and a crank case enclosing the working parts of the motor and adapted to contain oil for lubricating the said parts by the splash system, of a pump formed in said valves, means for 105 supplying the oil in the crank case to said pump, and means for conveying the oil from the pump to various parts of the motor.
18. The combination with a stationary 110 casing having intake and outlet ports, of a pump cylinder movable relative to the casing and having an annular recess and a port 115 adapted to register with the ports in said casing, a pump piston having an annular enlargement fitting said recess and movable relative to the cylinder and to the casing, and means for moving said cylinder and piston.
19. In a motor, the combination with the 120 casing having intake and exhaust ports, the piston in the casing, and the superposed sliding sleeves controlling said ports, said casing having oil inlet and outlet ports and the outer of said sleeves having a pocket adapted to register with said inlet and outlet ports at different times, and means for 125 sending a charge of air through said pocket at the time it registers with said outlet port.
20. In a motor, the combination with the 130 casing having intake and exhaust ports, the piston in the casing, and the superposed sliding sleeves controlling said ports, said casing having oil inlet and outlet ports and the outer of said sleeves having a pocket adapted to register with said inlet and outlet ports at different times, and means oper-

ated by the sleeves for sending a charge of air through said pocket at the time it registers with said outlet port.

21. In a motor, the combination with the casing having intake and exhaust ports, the piston in the casing, and the superposed sliding sleeves controlling said ports, said casing having oil inlet and outlet ports and the outer of said sleeves having a pocket adapted to register with said inlet and outlet ports at different times, and a pump formed in said sleeves adapted to send a charge of air through said pocket at the time it registers with said outlet port.

22. In a motor, the combination with the casing having intake and exhaust ports, the piston in the casing, and the superposed sliding sleeves controlling said ports, said casing having oil inlet and outlet ports and the outer of said sleeves having a pocket adapted to register with said inlet and outlet ports at different times, said inner sleeve also having an enlarged bore at its lower end and said outer sleeve being enlarged to fit said bore, whereby a chamber is formed between the sleeves which expands and contracts as the sleeves are relatively reciprocated, and said outer sleeve having a passage extending from said chamber and adapted to register with said pocket at the same time said pocket registers with said outlet port.

23. In a motor, the combination with the casing having intake and exhaust ports, the piston therein, and the two superposed sleeves controlling said ports, said casing having air inlet and outlet ports arranged in different transverse planes and the outer of said sleeves having a port adapted to register with said air ports at different times, a pump formed in said sleeves and communicating with the port in said outer sleeve, and means for reciprocating said sleeves relative to the casing and to each other.

24. The combination with a motor comprising a casing, a piston therein, and a pair of relatively movable valve sleeves controlling the ports of the motor, of a pump formed in the ends of said sleeves, and a compression tank having pipe communication with said pump.

25. The combination with a casing having inlet and outlet ports in different trans-

verse planes, a relatively immovable end wall in said casing, and having a port cooperating with one of the ports in said casing and a piston working in the casing, of a plurality of concentric sleeves or sliding valves controlling said ports, and positively operating means for sliding said valves.

26. The combination with a casing having inlet and outlet ports in different transverse planes, a relatively immovable end wall in said casing, and having a port cooperating with one of the ports in said casing and a piston working in the casing entirely beyond said port, of a plurality of concentric sleeves or sliding valves controlling said ports, and positively operating means for sliding said valves.

27. The combination with a motor having a sliding valve, of a pump of which said valve forms the piston, the ports of said motor and pump being independent. 75

28. In an engine, the combination with a cylinder and a relatively sliding valve, of a pump of which said valve forms a part, the ports of said pump being independent of the ports of the engine. 80

29. In a motor having two valve sleeves sliding one on the other, a pump barrel formed in one of said sleeves, a piston formed in the other sleeve, said sleeves having ducts formed in them to connect with the pump outlet, and means for relatively reciprocating said sleeve.

30. In a hydrocarbon motor having valve sleeves sliding one on the other between the piston and the cylinder, a pump barrel 90 formed in one of said sleeves, a piston formed in the other sleeve, and means for relatively reciprocating said sleeves.

31. In a hydrocarbon motor having valve sleeves sliding one on the other between the piston and the cylinder, a pump barrel 95 formed in one of said sleeves, a piston formed in the other sleeve said sleeves having inlet and outlet ports for said pump, and means for relatively reciprocating said sleeves. 100

In testimony whereof I affix my signature in presence of two witnesses.

MILTON TIBBETTS.

Corrections in Letters Patent No. 1,113,510.

It is hereby certified that in Letters Patent No. 1,113,510, granted October 13, 1914, upon the application of Milton Tibbetts, of Detroit, Michigan, for an improvement in "Engines," errors appear in the printed specification requiring correction as follows: Page 5, line 47, for the word "including" read *inclosing*; page 6, line 77, before the word "valve" insert the word *sleeve*; and that the said Letters Patent should be read with these corrections therein that the same may conform to the record of the case in the Patent Office.

Signed and sealed this 17th day of November, A. D., 1914.

[SEAL.]

R. F. WHITEHEAD,
Acting Commissioner of Patents.
